UNITED STATES PATENT OFFICE.

HUGH V. CONRAD, OF PITTSBURGH, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

VALVE MECHANISM FOR AIR-COMPRESSORS.

1,096,828.

Specification of Letters Patent.

Patented May 19, 1914.

Application filed December 19, 1910. Serial No. 598,077.

To all whom it may concern:

Be it known that I, HUGH V. CONRAD, a citizen of the United States, residing at Pittsburgh, in the county of Allegheny and 5 State of Pennsylvania, have invented new and useful Improvements in Valve Mechanism for Air-Compressors, of which the following is a specification.

This invention relates to the fluid inlet 10 valve mechanism of a fluid compressor, and has reference more particularly to compressors designed to run at high speeds, such, for example, as those driven by direct connection to an electric motor.

15 There are some advantages to be gained by the employment of a high speed compressor of the above character, such as dispensing with reducing gears between motor and compressor crank shaft, the reduced size 20 of motor required on account of the higher operating speed of the motor, and the increased capacity of the compressor for a given size, due to the higher operating speed of the compressor. It has, however, 25 been found that the safe speed at which the compressor inlet valves may be operated is limited, owing to the liability at high speeds of the valves and valve stems breaking due to the greater impact effect of the valves and 30 the increased tendency at such speeds of the valve and valve stem material to crystallize and thus facilitate breakage of parts and furthermore, at high speeds the valves can not act rapidly enough in the opening and 35 closing movements by reason of the increased momentum of the parts.

The principal object of my invention is to remedy this difficulty and for this purpose I propose to employ two inlet valves for each 40 compressor cylinder which are adapted to operate alternately, one opening on one suction stroke of the compressor and the other opening on the next suction stroke, so that the speed of each inlet valve is only one half 45 that of a single inlet valve under the same conditions and the speed of the inlet valves is thus reduced to within safe working limits.

50 In the accompanying drawing, Figure 1 is a sectional view taken substantially on the line *a—a* of Fig. 2 of an air compressor with my improvement applied thereto and Fig. 2 a front elevational view thereof, partly in section.

As shown in the drawing, the compressor 55 may comprise the usual casing 1 having an air cylinder 2 containing piston 3 connected by rod 4 to the crank shaft 5, said crank shaft being connected up to an electric motor or other desired source of power. 60

The compressor cylinder is provided with the outlet valves 6 of the usual puppet type, and according to my invention, each cylinder is also provided with two inlet valves 7 and 8 having the respective valve stems 9 65 and 10. For operating the inlet valves a cam shaft 11 is provided having secured thereto cams 12 and 13 and being provided with a gear 14 adapted to mesh with a pinion 15 on the crank shaft 5. Loosely 70 mounted in the casing 1 are pins 16 and 17 adapted at one end to engage the respective ends of the valve stems 9 and 10 and having their opposite ends in engagement with pivotally mounted fingers 18 and 19 respectively. The fingers 18 and 19 are arranged to bear on the cam surfaces of the cams 12 and 13 and said cams are adjusted 180 degrees apart, so that one of the pins 16 and 17 is operated at each half revolution of the 80 shaft 11. The gear 14 and the pinion 15 are in the ratio of two to one, so that the cam shaft 11 makes one revolution for every two revolutions of the crank shaft 5.

It will now be evident that when the compressor is running, each inlet valve is operated only every other suction stroke of the compressor thus reducing the movements of each inlet valve to one half that of a single inlet valve applied to a compressor operating at the same speed and thereby minimizing the danger of valve breakages as well as securing a more efficient action of the valves. 85 90

While a duplex or double cylinder air compressor is illustrated in the drawing, it will 95 be understood that my improvement may be applied to compressors having one or more cylinders such as single stage and double stage or compound compressors.

Having now described my invention, what 100 I claim as new and desire to secure by Letters Patent, is:—

1. The combination with a fluid compressor cylinder, of two inlet valves for controlling the admission of fluid to one end of the 105 compressor cylinder and means for actuating said valves at different times.
2. The combination with a fluid compres-

sor cylinder, of two inlet valves for controlling the admission of fluid to one end of the compressor cylinder and means for alternately actuating said inlet valves.

5. A fluid compressor comprising a casing having a cylinder, a piston therein, an outlet valve for permitting the outflow of compressed fluid from the cylinder, two inlet valves for controlling the admission of fluid to said cylinder at one end of the piston, and means for alternately actuating said inlet valves.

10. 4. The combination with a fluid compressor cylinder and a piston therein, of two inlet valves for controlling the admission of fluid to the compressor cylinder at one end of the piston and means for actuating each

inlet valve on alternate suction strokes of the piston.

5. The combination with a fluid compressor cylinder and a piston therein, of two inlet valves for controlling the admission of fluid to the compressor cylinder at one end of the piston and means for actuating said inlet valves in alternate succession corresponding with the suction strokes of the piston.

20 25
In testimony whereof I have hereunto set my hand.

HUGH V. CONRAD.
